Atty.

UNITED STATES PATENT OFFICE.

HENRY SANDER, OF BALTIMORE, MARYLAND.

COFFIN.

SPECIFICATION forming part of Letters Patent No. 244,317, dated July 12, 1881.

Application filed January 17, 1881. (Model.)

To all whom it may concern:

Be it known that I, HENRY SANDER, of the city of Baltimore and State of Maryland, have invented certain Improvements in Coffins, of which the following is a specification; and I do hereby declare that in the same is contained a full, clear, and exact description of my said invention, reference being had to the accompanying drawings, and to the letters 10 of reference marked thereon.

This invention relates to improved means for preventing what is termed the "resurrection of bodies"—that is to say, the unauthorized removal of corpses from coffins after 15 burial; and the invention, briefly stated, consists in providing the interior of the coffin with a series of transverse bars, which pass entirely around and underneath the corpse and are tied together below the lid and locked. 20 These transverse bars are united by longitudinal straps, and form, with them, a barred or grated envelope, which will sustain the body in case the wood-work of the coffin is removed.

In the further description of my said invention which follows, reference is made to the accompanying drawings forming a part hereof, and in which—

Figure I is a longitudinal section of the improved coffin or casket. Fig. II is a cross-section of the invention. Fig. III is a plan of the invention with the upper portion of the wood-work removed. Fig. IV is a view of certain parts of the invention on an enlarged scale.

Similar letters of reference indicate similar 35 parts in all the views.

A is the coffin or casket proper, and B the removable top or lid of the same. C C are shutters, one of which may be removed independently of the lid B.

40 D D and E E are respectively longitudinal straps and transverse bars extending across the bottom of the casket and up the sides of the same, to which they are fastened in any appropriate manner. The ends of the bars E are perforated and secured to plates F, which 45 have suitable eyes, and are fastened underneath the coffin-lid or the shutters by means

of bolts a. One or more of the bolts a, when in place, are locked by means of screws b, which enter into the said bolts from the exterior of the casket, as shown. A second screw, c, may be used to lock the first if additional security is required.

It will be seen that the straps and bars D and E, together with the plates F and the connecting-bolts, form a grated envelope, from 55 which the corpse cannot be removed if the wooden lid is entirely destroyed.

The arrangement of the bars and straps will necessarily have to be altered to suit different kinds of coffins and caskets; but such alteration in detail will not affect the nature of 60 my invention.

I am aware that it is not new to bind the several parts of a coffin together by means of 65 metallic straps and angle-plates, and screws to pass through the lid into the metallic straps; also, that coffins have been provided with automatically-clasping devices for holding the lid to the body part.

I am also aware that coffins have been fitted with a false bottom, to which the body or corpse is secured by means of straps, the said 70 false bottom being fastened to the bottom proper in order to prevent removal; but I am not aware that prior to my invention a coffin 75 has had secured to its inner surface a series of transverse bars connected underneath the lid by removable bolts and fastened with locking devices, the said transverse bars being connected by longitudinal straps to form a grated or barred envelope to sustain the corpse and 80 prevent its withdrawal after the destruction of the wood-work or outer covering.

I therefore claim as my invention—
85 In combination with the coffin or casket proper, A, and lid B, the transverse bars E, plates F, bolts a, and screws b, substantially as herein specified.

H. SANDER.
